(57) **CLAIM**

The ornamental design for an attachment bracket for a stair railing, as shown and described.

DESCRIPTION

FIG. 1 is a perspective view of an attachment bracket for a stair railing my new design.

FIG. 2 is a front elevation view thereof.

FIG. 3 is a right side elevation view thereof.

FIG. 4 is a rear elevation view thereof.

FIG. 5 is a left side elevation view thereof.

FIG. 6 is a top plan view thereof.

FIG. 7 is a bottom plan view thereof; and,

FIG. 8 is an environmental front elevation view of the attachment bracket for a stair railing shown mounted to a vertical surface and receiving the end of a stair railing. The broken lines rendered in FIGS. 1-7 of the drawings illustrate portions of the attachment bracket for a stair railing and form no part of the claimed design. The broken line showing of the vertical surface and stair railing, in FIG. 8, illustrates the environment of the claimed design and forms no part of the claimed design.

1 Claim, 5 Drawing Sheets
